GEORGE D. PARKER, OF RIVERSIDE, CALIFORNIA.

ELEVATING AND STACKING APPARATUS FOR FIELD-RECEPTACLES.

1,292,636.

Specification of Letters Patent. Patented Jan. 28, 1919.

Application filed October 22, 1918. Serial No. 259,239.

To all whom it may concern:

Be it known that I, GEORGE D. PARKER, a citizen of the United States, residing at Riverside, in the county of Riverside and State of California, have invented certain new and useful Improvements in Elevating and Stacking Apparatus for Field-Receptacles, of which the following is a specification.

10 In delivering fruit from the field to packing houses for treatment, such as grading, sizing and packing thereof, it is picked by the producer and deposited in what are termed field boxes or receptacles, which are 15 of standard and uniform size, and in this condition is transported to the packing houses. In delivering these field receptacles to a packing house it is desirable that the same be formed in stacks or vertical rows, 20 as it is easier to handle the boxes in this manner, and the same require less floor space than if they are unstacked.

The present invention relates to an apparatus adapted for receiving the filled field 25 receptacles and successively stacking and elevating the same in a vertical row and transferring successively formed vertical rows onto a suitable truck or conveyer or other support. The principal objects of the invention are to provide mechanisms controlled and operated by the filled receptacles 30 for throwing elements into and out of operation, which cause the operation of the device on power being applied thereto.

35 With the above mentioned and other objects in view, the invention consists in the novel construction and combination of parts hereinafter described, illustrated in the accompanying drawings and pointed out in 40 the claims hereto appended; it being understood that various changes in the form, proportion, size and minor details of construction within the scope of the claims may be resorted to without departing from the spirit 45 or sacrificing any of the advantages of the invention.

To more fully comprehend the invention, reference is directed to the accompanying drawings, wherein—

50 Figure 1 is a view in side elevation of the preferred embodiment of my invention, illustrating in dotted lines the position of the stacking frame when moved to deposit the

stack of elevated receptacles onto a suitable support. 55

Fig. 2 is a view in top plan, illustrating the control and operating means.

Fig. 3 is a sectional view taken on line 3—3 of Fig. 2, viewed in the direction of 60 the arrows.

Fig. 4 is a view in broken detail of one of the controlling clutches.

Fig. 5 is a vertical sectional view of one of the controlling clutches.

Fig. 6 is a view in detail of the receptacle 65 actuated clutch selective plate.

Fig. 7 is a view in detail of one of the receptacle elevating brackets.

Referring more particularly to the several views of the drawings, wherein like characters of reference designate corresponding parts, the numerals 1 indicate suitable parallel spaced bases above and between which are supported, preferably by trusses 2, the parallel spaced conveyer side members or rails 70 3 downwardly inclined toward one end of the bases 1, said side members being connected by the conveying rolls 4 extending transversely between the same and mounted to rotate at their opposite ends in said respective rails. The filled field receptacles are deposited on the elevated end of the conveyer and roll by gravity to the lower end thereof, as illustrated in dotted lines—Fig. 1 of the drawings. 85

Vertically disposed at the lower end of the conveyer is a stacking frame formed of the corner members 5, preferably four in number, the lower ends of which are spaced above the base members 1 and said corner 90 members are preferably disposed, two directly over each of the base members 1, as in Fig. 2 of the drawings.

Suitable links 6 connected at one end as at 7 to their respective frame members, and 95 at their opposite ends, as at 8 to the bases 1, support said frame members in a vertical position. Adjacent their upper ends the links at opposite sides of the frame are pivotally connected by connecting members 9, 100 and to one end of said members 9 are connected the frame moving links 10 attached at their lower end, as at 11, to the operating cranks 12 carried on the opposite ends of the shaft 13. The shaft 13 is rotatably mounted 105 in bearings 14 carried by the bases 1 and

extends transversely thereof beneath the conveyer.

Extending parallel with the bases 1 and fulcrumed at one end to brackets 14 at one end of the bases are the receptacle elevating rods or members 15 which terminate at their free ends at points between the corresponding corner frame members at opposite sides of the frame. Within their length said elevating members are connected through links 16 with the cranks 17 carried at opposite ends of a rotatable shaft 18 mounted in bearings 19 on the bases 1.

Pivottally mounted as at 20 on the inner faces of the free ends of the members 15 are the oppositely disposed receptacle engaging and elevating brackets 21 formed with inwardly projecting flanges 22, which when the brackets are in their lowermost position lie slightly below and adjacent to the outer edge of the side rails 3 and over which the receptacles come to a point of rest on arriving at the lower end of the runway. The flanges 22 are hinged as at 23 to the brackets 21 and are normally maintained in a horizontal position by springs 24 secured at one end to the flange 22 and at their opposite end to the arm 25 extending below the bracket 21 and with which contacts the lip 26 carried by the flange 22 when the same is in a horizontal position. This construction of the brackets enables the same to pass downwardly over a receptacle should the same arrive at the lower end of the runway when the brackets are in their elevated position, as hereinafter described.

As the receptacles successively arrive at the lower end of the runway, the same are elevated within the frame by the brackets 21 which are operated in the following manner.

Mounted at the lower end of the runway is a receptacle tripped lever 27 fulcrumed as at 28 and connected within its length through a link 29 with a clutch selecting plate 30, the link 29 being provided with a headed member 31 which operates in a slotted guide 32 extending longitudinally of said plate 30. The plate is pivotally supported beneath one of the rails 3 by a suitable link 33, and extended from the opposite side thereof in line with one end of the slot 32 is an operating link 34 pivotally attached to one arm of a bell crank 35 pivotally supported as at 36 to a fulcrum member carried by the bracket 37. The free arm of the bell crank is provided with a beveled plate 38 which is adapted on the movement of the bell crank for swinging into and out of the path of rotation of a suitable clutch dog 39 carried by a clutch hub 40 keyed to rotate with the shaft 18. The shaft is rotated by power applied through the drive gear 41 loosely mounted on said shaft, the hub of which is interiorly bored, and is provided with recesses 42 for receiving said dog 39,

which is outwardly pressed by a spring 43, thereby uniting the gear 41 and hub 40. The bevel of the plate 38 is in the direction of rotation of the shaft 18, and a receptacle contacting with the trip arm 27 will through links 29 and 34 and plate 30 throw the free end of the bell crank 35 from within the path of movement of the pawl, 39, permitting the same to engage in one of the notches 42. The gear 41 is adapted to be continuously rotated in the direction of the arrows, Fig. 1 of the drawings, by the pinion 44 carried by a shaft 45 rotatable in bearings 46 and driven through power applied thereto through a sprocket gear 47. The receptacles successively moving by gravity down the conveyer by the weight thereof trip the lever 27, which through the various connections causes the removal of the plate 38 from contact with the pawl 39, permitting the pawl to provide a driving connection between the gear 41 and shaft 18.

The operation of the gear in the direction of the arrows, Fig. 1, raises the free end of the elevating bars 15, causing the engagement of the underside of the positioned receptacle by the plates 22, one at each end thereof, and the continued movement of the members 15 raises the receptacle upwardly between the corner members 5 and between the pivoted retaining dogs 47, one pivotally mounted as at 48 to a bracket carried by each of the corner members 5, and which dogs retain the elevated receptacle in its raised position during the lowering movement of the members 15 and the completion of rotation of shaft 18.

The raising of the positioned receptacle from the lower end of the runway releases the pressure exerted thereby on the trip lever 27, permitting said lever to be restored to its normal position by a spring 49 connected therewith, and thus throwing the beveled edge 38 of the bell crank 35 into the path of rotation of the pawl 39 which causes a disengagement of the pawl from its associated recess on the completion of the revolution of the shaft 8, at which time the brackets 21 are in their lowermost position, as in Fig. 1 of the drawings, and are ready to elevate a succeeding receptacle as positioned thereover.

It will be apparent that the receptacles successively traveling down the conveyer trip the lever 27, which causes an operation of the elevating means, which, in turn, raises the lever actuating receptacle within the elevating frame, the driving gear 41 in carrying out this operation making one complete revolution and on assuming a position whereby the brackets 21 are in their lowermost position is brought to a point of rest. The receptacles in their movement by gravity down the runway pass between and operate the gates 50, carried one by each of the

corner frame members 5 between which the receptacles pass, said gates being pivoted to swing on a vertical axis, as at 51, in the direction of movement of the receptacles, 5 and the same are restored to normal position in alinement with each other by springs 52, one coöperating with each gate.

The receptacles as successively elevated within the elevating frame rest on each other 10 in superimposed relation and after a sufficient number have been elevated in stack formation, five being illustrated in the drawings, it is desired to bodily move the same, together with the sixth receptacle about to 15 trip the lever 27, to a truck or other conveying means 61, and to position the same thereon in stack formation, and in carrying out this operation the following mechanism is employed.

20 Vertically disposed adjacent one of the inner corner members 5 of the frame and carried by a support 52' is a stack operated clutch control rod 53 carrying at its upper end an arm 54 lying within the path of 25 movement of the elevated receptacles within the frame and preferably positioned in line with the upper end of its coöperating corner member 5. The lower end of the rod 53 connects with one end of a pivoted bell 30 crank 55 supported by said support 52', the opposite end of said bell crank being connected through a link 56 with the link 29 intermediate of its length. On the longitudinal upward movement of the rod 53 by 35 contact of the uppermost receptacle within the frame with the arm 54, the link 56 is longitudinally moved to shift one end of the link 29 from a position in line with the link 24 to the opposite end of the slot 32, as 40 in dotted lines Fig. 2 of the drawings.

Pivottally connected with the outer end of the plate 30, adjacent the outer end of the slot 32, is a link 57 which coöperates at its opposite end with a bell crank 58 of the 45 same construction as the bell crank 35, and which bell crank 58 operates a clutch pawl of the exact type and construction as illustrated in Figs. 4 and 5 of the drawings, the clutch controlling the connection of a driving gear 60 with its supporting shaft 13, said gear 60 being driven in the direction of the arrows, Figs. 1 and 2 of the drawings, by the pinion 44.

On the moving of the link 20 to the dotted 55 line position, Fig. 2 of the drawings, by the uppermost receptacle of the stack contacting with the arm 54, the next receptacle passing by gravity down the runway throws the trip arm 27, which through the link 24 60 the inner end of which is now in the outer end of the slot 32, causes a pivoting of the plate 30 on the outer end of the link 33, the pivotal movement thereof being greater at its outer end than at its inner end and being 65 sufficient at its outer end to cause the oper-

ation of the bell crank 58 through the link 57 without operating the bell crank 35. This movement of the bell crank 58 completes a driving connection between the gear 60 and shaft 13. The rotation of the shaft 70 75 13 through the cranks 12 causes a reciprocation of the links 10, the outward movement of which forces the frame corner members 5 in unison downwardly and outwardly in an arcuate path, said frame members carrying the five elevated receptacles. The gates 50 carried by the inner frame members are moved therewith contacting with the lever operating receptacle at the lower end of the runway forcing the same longitudinally of 80 and from the lower end of the runway onto a suitable truck or other member 61 positioned adjacent the ends of the bases 1. The completion of the downward movement of the frame over the truck 61 deposits the receptacles held therein onto the lowermost receptacle moved thereby onto the truck and the resting of the elevated receptacles onto this lowermost receptacle causes a spreading or disengagement of the dogs 47 from 85 the lowermost receptacle of the elevated stack, permitting the stack of receptacles to rest on this lowermost receptacle. The rearward reciprocation of the link 10 moves the frame upwardly and inwardly in an arcuate 90 path from the stack of receptacles resting on the truck, the dogs 47 scraping on the sides of the receptacles without dislodging the same from their elevated position.

Thus it will be apparent that the frame 100 is returned to its normal position, at which time the spring 49' will have moved the bell crank 58 to its normal position to interrupt the clutch dog coöperating with the same, which will arrest the rotation of the shaft 105 13 on the completion of its rotation until such time as a new stack of receptacles is formed within the elevating frame.

The depressing of the lever 27 when the end of the link 29 is in the outer end of 110 the slot 32 causes a forward swinging of the plate 30, which disposes the slot 32 with its outer end nearest the lever 27. In this position, the weight of the rod 53 and its associated parts is not sufficient to return the 115 link 29 to normal position, as in full lines, Fig. 2 of the drawings, owing to the angle of disposition of slot 32 and tension on link 29. However, on the completion of the removal of the lowermost receptacle from contact with the lever during the movement of the receptacle stack, the spring 49' restores said plate 30, through the link 29, to normal position, and at this time the weight of the rod 53 and its associated parts, from 120 beneath the upper end of which the topmost elevated receptacle has been removed, automatically returns the link 29 to normal position indicated in full lines, Fig. 2, permitting the next succeeding box to trip the 125 130

lever 27, which will in turn operate the receptacle elevating means.

Having thus described my invention, what I claim as new and desire to protect by Letters Patent is:—

1. A receptacle elevating and stacking apparatus comprising a conveyer for the filled receptacles, means disposed above the conveyer for retaining the receptacles in raised position as successively elevated in superimposed relation one resting on another, means operated by successive receptacles arriving within the sphere of said retaining means for elevating the same one at a time, and receptacle controlled means for moving said stack of raised receptacles as a unit and for depositing the same on a suitable support removed from said conveyer.
2. A receptacle elevating and stacking apparatus comprising a conveyer for the filled receptacles, means disposed above the conveyer for retaining the receptacles in raised position as successively elevated in superimposed relation one resting on another, means operated by successive receptacles arriving within the sphere of said retaining means for elevating the same one at a time, and means thrown into operation by a receptacle arriving within the sphere of said retaining means for moving said stack of raised receptacles as a unit and for depositing the same on a suitable support removed from said conveyer.
3. A receptacle elevating and stacking apparatus comprising a conveyer for the filled receptacles, means disposed above the conveyer for retaining the receptacles in raised position as successively elevated in superimposed relation one resting on another, means operated by successive receptacles arriving within the sphere of said retaining means for elevating the same one at a time, means thrown into operation by a receptacle arriving within the sphere of said retaining means for moving said stack of raised receptacles as a unit and for depositing the same on a suitable support removed from said conveyer, and means movable with said stack of elevated receptacles for moving the operating receptacle to said support for receiving said stack of receptacles as deposited thereon.
4. A receptacle elevating and stacking apparatus comprising a conveyer for the filled receptacles, a frame disposed above said conveyer for receiving the receptacles as successively raised therein in superimposed relation one resting on another, means for retaining the receptacles in raised position within the frame, a support for said frame whereby the same is capable of movement from over said conveyer and maintained in vertical position during such movement, means for elevating the receptacles within said frame as successively positioned below

the lower end thereof, means thrown into operation on the elevating of a predetermined number of receptacles within said frame for causing operative movement of said frame on the delivery of another receptacle beneath the same, and means thrown into operation on a receptacle arriving beneath said frame for moving said frame to deposit the receptacles held therein as a stacked unit onto a suitable support removed from said conveyer and for returning the emptied frame to normal position.

5. A receptacle elevating and stacking apparatus comprising a conveyer for the filled receptacles, a frame disposed above said conveyer for receiving the receptacles as successively raised therein in superimposed relation one resting on another, means for retaining the receptacles in raised position within the frame, a support for said frame whereby the same is capable of movement from over said conveyer and maintained in vertical position during such movement, means for elevating the receptacles within said frame as successively positioned below the lower end thereof, means thrown into operation on the elevating of a predetermined number of receptacles within said frame for causing operative movement of said frame on the delivery of another receptacle beneath the same, and means thrown into operation on a receptacle arriving beneath said frame for moving said frame to deposit the receptacles held therein as a stacked unit onto a suitable support removed from said conveyer and for returning the emptied frame to normal position, and means movable with said frame for engaging and moving the frame operating receptacle to said support for receiving and supporting said stack of receptacles as deposited thereon.

6. A receptacle elevating and stacking apparatus comprising a conveyer for the filled receptacles, a stacking frame vertically disposed above said conveyer and within which the receptacles are successively elevated in superimposed relation one resting on another, means controlled by successive receptacles arriving beneath said stacking frame for elevating the same one at a time within said frame, means for moving said frame with the elevated receptacles therein from above said runway to deposit said receptacles in stacked formation on a suitable support and for returning said frame to normal position, means operated by a receptacle within said frame for throwing said frame moving means into operative position, and receptacle operated means for throwing said frame moving means into operation to cause movement of the frame to deposit the receptacles held therein on a suitable support removed from said conveyer.

7. A receptacle elevating and stacking apparatus comprising a vertically disposed

- frame open at its lower end, a plurality of supporting links connected to said frame and supporting the same, said links providing a fulcrum for said frame, operating means 5 connected with said frame for moving the same on its fulcrum and for returning the same to normal position, means for successively elevating the receptacles within said frame, means for retaining the receptacles in 10 elevated position within said frame in superimposed relation one resting on another, and means thrown into operation by the elevating of a predetermined number of receptacles within said frame for causing movement 15 of said operating means for moving said frame to deposit the receptacles held thereon as a unit on a suitable support removed from said elevating means.
8. A receptacle elevating and stacking apparatus comprising a vertically disposed stacking frame open at its lower end, means for supporting said frame and capable of operation for moving the same laterally in an arcuate path and for retaining the same 20 in a vertical position during such movement, a receptacle runway extending beneath said frame for delivering receptacles below the lower end thereof, means at the lower end of
- said frame for successively elevating the receptacles delivered below the frame upwardly thereinto, operating means for said frame supporting members, operating means for said receptacle elevating means, a drive member, independent clutch mechanisms between the drive member and said frame 30 operating means and said receptacle elevating operating means, a clutch selective plate connected to both of said clutch mechanisms, a lever connected with said plate through a movable member and operated by said receptacles as successively positioned beneath the same for operating said clutch mechanisms one at a time, and means operated by the elevation of a predetermined number of receptacles within said frame for positioning the movable member associated with said lever relatively to said plate to select the clutch mechanism to be operated on the next operation of the lever.
- In testimony whereof I have signed my name to this specification in the presence of two subscribing witnesses.
- GEORGE D. PARKER.
